UNITED STATES PATENT OFFICE.

ROBERT P. RALSTON, OF NEW CONCORD, OHIO.

POPPER, TOASTER, AND BAKER COMBINED.

1,157,326.

Specification of Letters Patent. Patented Oct. 19, 1915.

Application filed February 27, 1915. Serial No. 10,963.

To all whom it may concern:

Be it known that I, ROBERT P. RALSTON, a citizen of the United States, residing at New Concord, in the county of Muskingum and State of Ohio, have invented a new and useful Popper, Toaster, and Baker Combined, of which the following is a specification.

My invention relates to improvements in poppers, toasters and bakers and has for its objects, first, to provide a device in which the above mentioned utensils, complete, are combined; second, to provide a device for the purposes mentioned, with a compact bottom which prevents the open flame of the gasoline, gas, or coal fire from coming in direct contact with the articles placed therein, and thereby avoids scorching or burning the same, and the absorbing of fumes, from the flame, as is the case with other devices of this nature now in use; and, third, to provide a baker and toaster that will prevent the articles placed therein from coming in contact with the hot smooth bottom, and thereby avoid scorching or burning of the same. I attain these objects by the invention illustrated in the accompanying drawing, in which—

Figure 1 is a view in perspective of the complete device when arranged as a corn popper; Fig. 2, a vertical section on the line x, x , Fig. 1, representing the lid partly elevated; Fig. 3, a view in perspective of the complete device when arranged as a baker and toaster; Fig. 4, a vertical section of the device on the line z, z , Fig. 3, representing the lid reversed and partly elevated; Fig. 5, a sectional view of the frame of the lid showing the method of securing the wire mesh in said frame; Fig. 6, a view in perspective of the detachable handle, and, Fig. 7, a vertical section of the detachable wooden handle.

With the exception of the wire mesh which forms a part of the lid, this device is constructed from sheet metal.

Similar figures refer to similar parts throughout the several views.

The body of the device, rectangular in shape, is formed with vertical sides, 1, 1, and with open ends excepting the metallic rolls, 12, 12, which extend across each end at the bottom and form a base on which the

reversible lid rests. The edges of the sides, 1, 1, are rendered rigid and smooth by the folds, 7, 7. The reversible lid consists of a metallic frame, 13, rendered sufficiently firm by a double fold, which firmly secures the wire mesh, 2, in said frame, and also, secures the metal strips, 6, 6, which together with the metal rolls, 12, 12, forms the ends of the complete device. The parts, 12, 12, are secured to the bottom of the device by rivets, 15, 15.

The rod, 3, passing through the metal roll, 14, and the slots, 4, 4, forms the sliding hinge on which the reversible lid operates. The slots, 4, 4, extend the entire length of the vertical sides, 1, 1, with a curve at one end for the purpose of allowing the hinge to drop to, and rest on the metallic roll, 12, as shown in Fig. 1. By grasping the ring, 5, the reversible lid is raised and the rod moves along the slots, 4, 4, thereby reversing said lid and it drops into position as shown in Fig. 3, converting the device into a baker and toaster, and the wire mesh, 2, which forms a part of the lid, now serves as a grill on which to place the articles to be toasted or baked. The detachable wooden handle, Fig. 6, is provided with a slot, 16, which admits the metal handle, 8, and is firmly held in place by the steel spring, 17, which passes through the openings, 18, and 9, in the respective parts of the handle. 85 The wooden part of the handle protects the hand from the heat of the metallic part, and may be easily removed and re-attached when necessary. The metallic part, 8, of the handle, is made of sheet metal, and rendered 90 sufficiently rigid by the folds, 10, 10, and is riveted to the bottom of the device by rivets, 11, 11.

This device can be used either over the open fire or by placing in the heated oven 95 of the ordinary cooking stove.

It will be seen that my invention is simple and inexpensive in construction, and strong and durable in its several uses.

What I claim as new, and wish to secure 100 by Letters Patent is—

In a device of the character described, having a rectangular body, with hinged lid, and metallic handle, said body comprising vertical sides and open ends excepting metallic rolls across said ends, said vertical

sides having slots cut longitudinally therein, extending the entire length thereof and curving downward at one end, said lid being constructed with metallic frame and wire mesh interior and a rod which operates in said longitudinal slots, by means of which said rod can be moved from one end of said

device to the other, thereby reversing and inverting said lid, substantially as described.

ROBERT P. RALSTON.
